UNITED STATES PATENT OFFICE.

ABIJAH S. PARKER, OF CINCINNATI, OHIO.

HUB-BAND.

SPECIFICATION forming part of Letters Patent No. 325,692, dated September 8, 1885.

Application filed August 4, 1884. (No model.)

To all whom it may concern.

Be it known that I, ABIJAH S. PARKER, a citizen of the United States, residing at Cincinnati, in the county of Hamilton and State 5 of Ohio, have invented certain new and useful Improvements in Hub-Bands, of which the following is a full, clear, and exact description, reference being had to the accompanying drawings, forming a part of this 10 specification.

My invention relates to an improvement in hub-bands for vehicles. It has for its object the production of hub-bands of wrought metal instead of cast. Ordinary cast hub-bands are 15 brittle and liable to break when being forced on the hub. In order to make a cast band sufficiently flexible, it must be annealed by a process requiring considerable time and expense. A cast band is also imperfect in shape and finish, and must be carefully turned on a lathe to make its form perfect, and to give it a smooth surface for either polishing or plating. All these difficulties and objections are overcome by making the band of wrought 20 metal of the desired thickness. It is then ductile, and will stretch and not break. The surface is smooth and finished, and readily polished or plated, and the band is not only much superior, but can be made with a saving of time and cost. I make these wrought 25 hub-bands from previously prepared seamless tubing of the proper size by subjecting it to pressure under properly-constructed dies.

My invention also consists in a further improvement in wrought hub-bands provided with an inner circular flange for attaching to the band an ornamental lining of thin sheet metal.

In the accompanying drawings, Figure 1 is 30 a sectional side elevation of the die and mandrel or plunger, and a section of seamless wrought tubing in process of manufacture into a hub-band. Fig. 2 is a similar section of a die for making the hub-band of a flat 35 sheet of metal. Figs. 3 and 4 represent the band complete. Fig. 5 shows a section of the sheet metal drawn into a tube before it has been subjected to the dies. Fig. 6 is a flat 40 sheet of metal cut into form for putting in the die. Fig. 7 is a side elevation in section of

the dies for making the hub-band with an inner circular flange. Fig. 8 is a hub-band partly cut away to show the interior flange.

The same letters of reference are used to indicate identical parts in all the figures.

A, Fig. 2, is a female die of the size and shape of the hub-band desired to be produced. The die A usually tapers slightly inward toward the bottom, making the lower circumference or diameter a little smaller than the 55 upper, so that the hub-band may be driven on the hub, though, if desired, it may have the same diameter throughout.

B is a mandrel or plunger of the same shape as the die A, and as much smaller as the thickness of the band to be produced. C is a sheet of wrought metal. E is a shoulder on the plunger, which fits into the space E' in the die when the two are brought together. The die A may be made open or closed at the bottom. 65 The upper edge of the die is made to flare outwardly, as shown at D, Fig. 2, and the mandrel B is provided with a corresponding space or recess, D'. As the mandrel B is forced down into the die the sheet of metal C 70 is carried before it, and is sufficiently ductile to take the shape of the die. There is thus formed a thimble, of which the smaller end is closed or solid. The upper edges are then 75 trimmed, leaving the flaring lip D'', Fig. 3, so and the bottom is cut off or out, leaving the end open, as shown at F, Fig. 3.

The die may be provided with a knife-edge so arranged around the bottom that the plunger, after completing the form, will press the 85 metal against this edge, so as to cut out the top of the thimble, thus forming and cutting the band at one operation. The hub-band is then complete, and is ready for polishing or plating, and need not be turned or shaped or 90 annealed.

Fig. 1 represents a similar die for making hub-bands of seamless wrought tubing. The section of tubing G is inserted in the die A, and as the die tapers slightly toward the bottom the section of tubing G will only go part of the way down without pressure, but will readily receive the bottom or smaller end of the plunger B. As the plunger is forced down, the section of tubing is carried with it by the 95 100

shoulder H, which also forms a lip or flare around the upper edge, as shown at D", Figs. 3 and 4; or the tubing G may be small enough to extend to the bottom of the die, when the 5 plunger will simply enlarge the upper portion and turn over the flaring lip D".

It is sometimes important to provide a hub-band with an interior circular flange, as that shown at P, Fig. 8, for attaching a thin ornamental lining. These flanges have heretofore been either cast or soldered in the band, and the thin metal lining soldered to the flange, or spun up into the band around the flange. To avoid the necessity of soldering into the 10 band such a ring or flange, and to make it an integral part of the hub-band, I subject the band, after heating it, if necessary, to pressure in dies so shaped as to upset the metal of the band itself to form such a flange. For forming 15 this circular flange within the band a somewhat different die is used, and this is preferably formed after the hub-band has been made, though it may be done at the same time.

In Fig. 7, A is a die similar to the one shown 20 in Figs. 1 and 2, except that a space, K, within the die is left around the top to receive the shoulder H of the mandrel. In the lower part of the die is placed a stationary former, L, as much smaller than the female die as the thickness 25 of the hub-band M. The upper edge of the die or former L is slightly beveled, as shown in the figure. The plunger N is made shorter than the die, the length of N and L being together equal to the depth of the die 30 from the space K downward, or to the entire length of the plunger in Figs. 1 and 2. The respective length of N and L is regulated by the point in the hub-band at which the flange 35 is to be made. The lower edge of the plunger 40 N, like the upper edge of L, is beveled to correspond to the size and shape of the flange desired. The band M is placed within the die, the lower portion being between the walls and the former L, and the space around the upper 45 part of the former being slightly wider than the space around its bottom. As the plunger

N is forced down, the shoulder H strikes the hub-band and carries it down upon itself, the effect being that the band is first thickened until it fills the space between the former L 50 and the smaller part of the plunger N and the walls of the die, and finally a portion of the metal of the band is upset, filling the space made by the beveled edges of the former and plunger, and producing a circular flange, P, 55 Fig. 8, corresponding in size, shape, and position with said space. The outside of the band remains straight and smooth. This flange, being of the same metal as the band, is, of course, ductile, and will not crack or break 60 when the band is stretched, but serves to strengthen it, as well as to form a bearing for fastening the thin ornamental lining, which may be spun up into the band and around the flange in the usual way. 65

While I have described the methods which I consider best for the manufacture of wrought or sheet metal hub-bands, I do not purpose to limit myself to these alone, for instead of forming the bands in dies it is evident that they 70 might be spun into the required shape.

The process herein described for forming wrought-metal hub-bands will form the subject of a separate application which I am now preparing; but, so far as the present application is concerned, I do limit myself to wrought-metal bands made from previously-prepared seamless tubing. 75

Having thus fully described my invention, I claim— 80

1. A wrought-metal hub-band made of previously-prepared seamless tubing, substantially as described. 85

2. A wrought-metal hub-band, made of sheet metal or tubing, having an interior circular flange upset from the metal of the band itself, substantially as described.

ABIJAH S. PARKER.
